DESIGN FOR A FLASHLIGHT

John Warren Kinney, Jr., Cincinnati, Ohio

Application September 19, 1944, Serial No. 115,366

Term of patent 14 years

(Cl. D48—24)

To all whom it may concern:

Be it known that I, John Warren Kinney, Jr., a citizen of the United States, residing at Cincinnati, in the county of Hamilton and State of Ohio, have invented a new, original, and ornamental Design for Flashlights, of which the following is a specification, reference being had to the accompanying drawings, forming part thereof.

Figure 1 is a front elevational view of a flashlight showing my new design;

Figure 2 is an elevational view of the left side of the flashlight shown in Figure 1;

Figure 3 is a top plan view of the flashlight;

Figure 4 is a rear elevational view of the flashlight;

Figure 5 is an elevational view of the right side of the flashlight.

I claim:

The ornamental design for a flashlight, as shown.

JOHN WARREN KINNEY, JR.
